CLUTCH BALANCING MACHINE

Raymond A. Massaccesi, Chicago, Ill., assignor to Allen Bagge and Gordon Hines, doing business as Balance Products Co., Hillside, Ill.

Filed Sept. 30, 1963, Ser. No. 76,784

Term of patent 14 years

(Cl. D52--6)

FIG. 1

FIG. 2

Fig. 3

Fig. 4

FIG. 1 is a perspective view of a clutch balancing machine showing my new design;

FIG. 2 is a side elevation of the clutch balancing machine;

FIG. 3 is a rear perspective view of the clutch balancing machine;

FIG. 4 is an enlarged fragmentary view of the panel portion of FIG. 1 of the drawings.

The dominant features of the design reside in the portions shown in full lines.

I claim:

The ornamental design for a clutch balancing machine, as shown and described.
